UNITED STATES PATENT OFFICE.

SEMON S. LEWIS, OF NEW YORK, N. Y.

FABRIC BOARD.

Application filed October 11, 1921. Serial No. 506,964.

To all whom it may concern:

Be it known that I, SEMON S. LEWIS, a citizen of the United States of America, residing at 210 West 110th Street, New York city, in the county of New York and State of New York, have invented certain new and useful Improvements in Fabric Board, of which the following is a specification.

This invention relates to devices on which 10 to wrap or wind fabric and is preferably termed a fabric board.

One important object of the invention is to provide a cheap form of fabric board of novel and improved construction.

15 A second important object of the invention is to provide an improved form of fabric board which can be built up from cardboard, pasteboard, or the like material and which will be light in weight and economical in 20 manufacture.

With the above and other objects in view, the invention consists in general of certain novel details of construction and combinations of parts hereinafter fully described, 25 illustrated in the accompanying drawings, and specifically claimed.

In the accompanying drawings, like characters of reference indicate like parts in the several views, and—

30 Figure 1 is a perspective view of fabric board constructed in accordance with this invention, a portion being broken away the better to show the construction.

Figure 2 is an end view thereof.

35 Figure 3 is a section, partly broken away, on the line 3—3 of Figure 2.

Figure 4 is a disassembled section on the line 4—4 of Figure 3.

40 Figure 5 is a detailed view showing the manner of locking the supporting strips together.

In the embodiment of the invention herein illustrated there is provided a shallow elongated tray 10 of pasteboard, cardboard, 45 or other like material and fitted within this tray 10 is a second similar tray 11 having substantially the same depth as the tray 10 but being just sufficiently shorter and narrower than the trays 11 and 10 nest together 50 snugly. It is to be noted that the bottoms of these trays form the sides of the reel body. Along each of the longitudinal edges of the tray 10 is secured a strip 12 which is preferably termed the edge strip and forms a half 55 round bead, the strip being bent to a semi-circular arcuate shape as clearly shown in

Figure 4. Between the bottoms of the trays 10 and 11 are provided suitable bracing strips which may also be formed from pasteboard or the like or may be formed from light wood or any other desired material. At least one of these strips extend longitudinally as indicated at 13 while the other strip extends transversely as at 14. The longitudinal strip is provided with notches 15 and the transverse strips are likewise provided with notches 16, these notches co-acting to hold the strips in position as shown in Figure 5. These strips preferably run from end wall to end wall of the trays and from side wall to side wall thereof so that the bottoms of the trays are prevented from collapsing toward each other. At each end the tray is bound with a suitable paper binding or covering 17 which serves to close the open ends 75 of the side beads and also to provide a neat finish at said ends.

With a fabric reel constructed in this manner it will be seen that the same may be made very cheaply and also that it will be light and strong.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. A fabric board consisting of an elongated shallow tray of cardboard like material, a second similar tray fitted within the sides and of substantially the same depth as of the first tray, the bottoms of said trays being oppositely disposed to form the main 100 side portions of the board, a semi-circular trough shaped cardboard strip secured to each of the longitudinal edges of the outer tray to form edge beads for said board, and interlocked spaced strips within the board 105 between the bottoms of the inner and outer trays to hold said bottoms against collapse, said strips extending from side to side and end to end of the trays in parallel relation to the end and side walls thereof respectively, 110 the strips extending from side to side engaging the sides of the trays and supporting the

same laterally against collapse through pressure of cloth wound on said board.

2. A fabric board consisting of an elongated shallow tray of cardboard like material, a second similar tray fitted within the sides and substantially of the same depth as the first tray, the bottoms of said trays being oppositely disposed to form the main side portions of the board, and interlocking spaced strips within the board between the bottoms of the inner and outer trays to hold

said bottoms against collapse, said strips extending from side to side and end to end of the trays in parallel relation to the end and side walls thereof respectively, the ends extending from side to side engaging the side walls of the inner tray and supporting the same against collapse under pressure from cloth wound on the board.

In testimony whereof I hereunto affix my signature.

SEMON S. LEWIS.
